(57) **CLAIM**

The ornamental design for an autonomous mobile cart, as shown and described.

DESCRIPTION

FIG. 1 is a front elevation view of an autonomous mobile cart showing our new design.

FIG. 2 is a rear elevation view thereof.

FIG. 3 is a right side elevation view thereof.

FIG. 4 is a left side elevation view thereof.

FIG. 5 is a top plan view thereof.

FIG. 6 is a bottom plan view thereof.

FIG. 7 is a top, left, front perspective view thereof; and,
FIG. 8 is a bottom, left, rear perspective view thereof.

The autonomous mobile cart is adapted for use in warehouses, factories, etc. For example, the autonomous mobile cart may autonomously travel between a preset departure point and destination while avoiding obstacles, etc., and conveys an object to be conveyed placed on its upper surface (carrying platform).

Elements drawn in broken lines represent portions of the autonomous mobile cart that form no part of the claimed design.
